UNITED STATES PATENT OFFICE.

JOHN ROSE, OF PHILADELPHIA, PENNSYLVANIA.

DESIGN FOR AN UMBRELLA BAND-CLASP FASTENER.

SPECIFICATION forming part of Design No. 29,819, dated December 20, 1898.

Application filed November 25, 1898. Serial No. 697,455. Term of patent 7 years.

To all whom it may concern:

Be it known that I, JOHN ROSE, a citizen of the United States, residing at the city of Philadelphia, in the county of Philadelphia and State of Pennsylvania, have invented and produced a new and original Design for an Umbrella or Parasol Band-Clasp Fastener, of which the following is a specification.

The leading feature of my said design consists of the shape or configuration of an umbrella band-clasp fastener, as hereinafter described, and illustrated in the accompanying drawings, in which—

Figure 1 is a top or plan view of the clasp-
fastener of the particular design of my said
invention. Fig. 2 is a side elevational view
of the same, and Figs. 3 and 4 are cross-sec-
tional views on the lines *xx* and *yy* of Fig. 1.

Referring to the drawings, A represents the
clasp-fastener of the particular shape or form
of my invention and consisting of the body
a, the face of which is concaved and with

parallel slits or openings *b* and *b'* on both sides thereof between said body and the outer peripheral slightly curved strips *c* and *c'*. 25 The back *d* of the device is truncated and has a central hole or opening *d'*. In the main body of the clasp, adjacent to each of the corners of the device, is provided a semicircular notch or recess *e* between the plain surface 30 edges *f* and *f'* of the said body, as clearly illustrated in Fig. 1 of the drawings.

Having thus described my invention, what I claim as new, and desire to secure by Letters Patent, is—

The design for an umbrella band-clasp fastener, substantially as shown and described.

In testimony whereof I have hereunto set my signature in the presence of two subscribing witnesses.

JOHN ROSE.

Witnesses:

J. WALTER DOUGLASS,
THOMAS M. SMITH.
